UNITED STATES PATENT OFFICE

VALENTINO RENZULLI, OF BRIDGEPORT, CONNECTICUT

EAVES-TROUGH-RAIN STRAINER

Application filed April 26, 1929. Serial No. 358,224.

This invention relates to articles made of wire strands suitably shaped and held together to form a cage-like structure, and in the embodiment herein shown as exemplary 5 thereof, the invention is applied to strainers for eaves troughs.

Such devices were customarily made of a number of vertical wires of suitable shape held laterally spaced from each other by 10 girthing wires which were interwoven with the vertical wires, as, for instance, as shown in a patent to Drendul, No. 380,873, April 10, 1888. Or, as shown in a patent to Minnemeyer, No. 536,038, March 19, 1895, the vertical wires were held together by annular bands having laterally spaced ears struck therefrom to be bent around the wires.

Both these previous proposals have inherent disadvantages, the former being difficult to make and requiring considerable time and labor, and the latter being liable to come apart in use, for the ears only partly encircle the vertical wires and could be easily bent out to cause the wires to be loose if not entirely free.

It is an object of the present invention to avoid these disadvantages and to provide a structure which is more durable and easily manufactured.

In carrying out this invention, there is provided a girthing band having eyes struck therefrom and laterally projecting so that the bent wires may be threaded through the eyes, after which the eyes are pressed in to 35 cause them to partially close and firmly grip the wires.

A further object of this invention is to provide a crown for the top of a dome-shaped wire structure so as to hold the wires 40 thereof properly spaced at that point and stiffen the entire structure.

An important feature of the present invention is the provision of means whereby the girthing band need not have any means 45 for holding its ends together in annular form, the band being so held by one of the vertical wires which interlocks with both ends of the band.

Other features and advantages will hereinafter appear.

In the accompanying drawings—

Figure 1 is a top plan view of the strainer for eaves trough drains made in accordance with this invention, portions of the device being broken away to show the construction. 55

Fig. 2 is a sectional view taken on the line 2—2 of Fig. 1.

Fig. 3 is a view looking at the device from the bottom.

Fig. 4 is a detail view of one of the wires 60 as formed previous to the assembling of the device.

Fig. 5 is a plan view of the strip from which the girthing band is made.

Fig. 6 is an edge view of the strip. 65

Fig. 7 shows the blank comprising the crown plate.

The cage-like structure of the present invention, as shown in the accompanying drawings, constitutes a strainer for eaves 70 trough drains and comprises an upper dome-shaped portion 10 and a lower or cylindrical portion 11 adapted to fit into the eaves trough drain pipe.

In common with previous devices of like 75 character, the device of the present invention comprises a plurality of wires 12, the upper portion 13 of which is bowed while the lower portion 14 is straight. These wires are preliminarily given the shape in a suitable bending fixture and may also be provided initially, as shown in Fig. 4, with a hook at the terminal end 15 of the bow-shaped portion 13 to engage a wire ring 16 when the wires 80 are assembled together. 85

According to the present invention, the wires, in the assembled relation shown in Figs. 1, 2 and 3, are held together properly spaced from each other at the junction 17 of the bowed portions 13 and straight portions 90 14 of the wire by a girthing band 18. This band, as shown in Fig. 5, is a relatively long, flat pliant, or even flexible, strip and has equi-spaced eyes or eyelets 19 formed by making parallel slits 20 in the band and 95 pressing down the material between the slits, as shown from the side in Fig. 6.

In assembling the device, a band 18 of the proper length, depending upon the diameter of the pipe the cylindrical end 11 of the 100

device is to fit, is cut from the girthing band strip. The assembler then threads the straight end 14 of a wire 12 through the next to the last eye 19 and bends the terminal end 15 of the wire around the top ring 16 either by forming a hook thereon by a suitable tool and closing the same around the wire ring 16, or, by merely closing the open hook when the latter is, as shown in Fig. 4, previously formed therein. These operations are repeated with each wire until each but the two end eyes 19 of the band contains a wire 12 which is fastened to the ring 16.

Then, to lock the two ends of the band 18 together, the assembler places the end eyes 19 upon each other and forces the last wire 12 through the aligned eyes and then clinches the terminal end 15 of the wire 12 around the ring 16.

For many purposes, the device as thus far described, is a satisfactory finished article and need have nothing further done to it in order that it may be used, especially when the junction of the bowed portion 13 and straight portion 14 of the wire 12 is provided with an inwardly extending kink 21, for in this case the wire, when threaded through the eye 19, will cause the metal of the strip 18 to spring slightly and firmly engage both sides of the kink or raised portion 21 of the wire 12.

However, in order that the device may be made very rigid, it is preferable to flatten down the eyes, by means of a suitable tool, as shown in Figs. 1 and 3, so that the band is firmly held to the wires.

To further strengthen and stiffen the structure of the device, the present invention provides a crown plate 22 which is formed from a blank, shown in Fig. 7, and has a plurality of equi-spaced notches 23 forming between them a series of tongues 24. The notches 23 are of such width that when placed on the tops of the assembled vertical wires 12, the tongues 24 fit between the wires and may be bent down and under the wires, and thus space the wires equal distances from each other in the vicinity of the ring 16 and, in addition, hold the wires together.

Variations and modifications may be made within the scope of this invention and portions of the improvements may be used without others.

Having thus described the invention, what is claimed as new and for which it is desired to obtain Letters-Patent, is:

1. An eaves trough drain strainer comprising a plurality of vertical wires; a ring upon which the upper ends of the wires are bent to fasten them together and to the ring; and a crown plate engaging said wires adjacent the ring to cover the ring and substantially close the hole thereof, to cover the ends of the wires connected thereto and to

hold the wires predeterminedly spaced from each other.

2. A device of the character described, having a plurality of wires; means connecting the wires together at their upper ends; and a crown plate having a plurality of spaced tongues around its periphery alternating with notches, said notches being adapted to receive vertical wires of the said device and said tongues being adapted to be bent through the spaces between the wires and clinched under the wires to hold the wires predeterminedly spaced from each other.

3. An eaves trough drain strainer comprising a plurality of vertical wires; a ring upon which the upper ends of the wires are bent to fasten them together and to the ring; a girthing band located between the ends of the wires and having integral eyelets projecting laterally from the band through which eyelets said wires extend to hold the wires predeterminedly spaced from each other; and a crown plate having a plurality of spaced tongues around its periphery alternating with notches, said wires extending into said notches and said tongues being bent through the spaces between the wires and clinched under the wires to hold the wires predeterminedly spaced from each other.

Signed at Bridgeport, in the county of Fairfield and State of Connecticut, this 17th day of April, 1929.
